UNITED STATES PATENT OFFICE.

LEON CAMMEN, OF NEW YORK, N. Y.

COOLING SYSTEM FOR INTERNAL-COMBUSTION ENGINES.

1,256,109.

Specification of Letters Patent. Patented Feb. 12, 1918.

Application filed June 29, 1917. Serial No. 177,719.

To all whom it may concern:

Be it known that I, LEON CAMMEN, citizen of the United States, and resident of New York city, in the county of New York and State of New York, have invented certain new and useful Improvements in Cooling Systems for Internal-Combustion Engines, of which the following is a specification.

This invention relates to cooling systems for internal combustion engines, and my improvements are directed to means whereby a constant, efficient temperature may be maintained in the jacket water.

Careful investigations of heat temperature control in automobile engines, made within the last two or three years, have shown that the higher the temperature of outgoing jacket water, the higher the efficiency of the engine (cp. paper by Kettering, *S. A. E. Bulletin*, 20 September 1916). J. B. Reploggle, director of research, Remy Electric Co. (*ibid.*, p. 703), "by controlling the temperature of the jacket until he began to boil the water, found that with all the rest of the equipment exactly the same as it had been, he increased the mileage of the machine from 18 to 31.6 miles per gallon".

There are however practical difficulties in the way of allowing the jacket water to boil, which have hitherto prevented any attempt to do it in practice. The average driver does not care to carry with him an extra supply of water, and to stop every couple of miles to refill the tank, especially as facilities for doing so may be often lacking. Condensation of the steam with the usual system of air current cooling is also impractical, as the condenser, as shown by cooling tower practice in steam plants, would have to be of prohibitive dimensions.

The present invention is based on the fact that, first, water may be conveniently cooled by a flow of air, and, second, it is easy to design and build a small size surface condenser to take care of the comparatively small amount of steam formed in the jackets. Moreover, as only condensation, and not vacuum is desired, there is no need of an air pump. In fact, the presence of air in the condenser is even desirable, as it raises the temperature of steam generation, and thus reduces the amount of steam formed.

Therefore my invention consists of a closed circuit water cooling system which includes the engine jacket, a radiator wherein temperature reduction is bounded by certain

limitations, and having means for the condensation and return of vapors generated in the circuit; also a secondary water cooling circuit which includes a usual form of radiator and an enclosure for the first named radiator and condensing means.

Each of the cooling systems may be operated by a pump; and one of them may be controlled by a valve which is operated through the functioning of a thermostat included in the other system.

Other features and advantages of my said invention will hereinafter appear.

In the drawing,

Figure 1 shows in side elevation a portion of a motor vehicle having my improvement represented, more or less diagrammatically thereon, and

Fig. 2 is a detail, enlarged view of the thermostatic valve.

Since I have elected to explain my invention as applied in motor car practice, let 1 indicate a chassis, 2 a motor thereon, and 3 the cooling jacket therefor.

A radiator consisting of water ducts 4, head 5 and base 6, is connected with the engine jacket as by pipes 7, 8, having circulating pump 9. Said radiator, which may be termed the closed circuit radiator, is inclosed within a water casing 10, which is connected with a usual form of radiator 11, as by pipes 12, 13, having a circulating pump 14. The radiator 11 is presented to the influence of cooling air, whose draft is increased as by a fan 15. Thus the closed circuit radiator is subjected to the influence of cooling water within casing 10. It is my purpose however to regulate the temperature of the water passing through casing 10, in order that by this means the water passing through the closed circuit radiator may be maintained at an efficient degree of temperature. Regulating means such as I may employ for this purpose will be described hereinafter.

Above casing 10 I provide another water casing 16 to inclose a condenser 17, which is in communication with the head 5 of the closed circuit radiator, so that steam or vapor entering said radiator will pass into said condenser, and permitting the products of condensation to return by gravity flow to said closed circuit radiator.

The casing 16 communicates, as by pipes 18, 19 with radiator 11, the pump 14 functioning equally in this service.

Assuming it to be desirable to maintain the temperature in the closed circuit radiator at around the boiling point, then it will be necessary to regulate the quantity of cooling water passing into casing 10 from radiator 11. This I may do as by placing a valve 19 in the pipe 12 and controlling said valve by a thermostat 20 in the pipe 7.

Obviously the particular arrangement and 10 location of the thermostatic valve members is not material, provided they perform the desired function, which is that of varying the volume of water entering casing 10 from the radiator, to thereby maintain an approximately constant temperature in the closed circuit radiator.

Assuming that it be desired to maintain the closed circuit radiator at the boiling temperature, then the thermostat will be set 20 accordingly, and will function to regulate the valve to the stated end, irrespective of atmospheric conditions.

With the water at the boiling point in the closed circuit radiator, steam generated 25 therein will pass into the condenser, but will not escape. The cool water from radiator 11, passing through casing 16, will restore the steam to liquid form, enabling it to return by gravity flow to the closed circuit radiator. Thus no loss in cooling water will 30 occur in the closed circuit, notwithstanding the relatively high and efficient temperature at which it is maintained.

In cases where alcohol or other volatile 35 anti-freezing agents are mixed with the cooling water, and which would be readily lost through evaporation if operating at high temperatures with the ordinary cooling systems, the advantage of the closed circuit will 40 be clearly apparent.

Variations may be resorted to within the spirit and scope of my said invention, and parts thereof used without others.

I claim:—

45 1. The method of cooling internal combustion motors which consists in circulating a fluid medium through a closed circuit in-

cluding an engine jacket and radiator, and circulating a liquid medium through a second circuit including an air cooled radiator, 50 in which second circuit a portion of the first circuit is immersed.

2. A cooling system for internal combustion motors comprising an engine jacket, a radiator, an inclosing casing therefor, means 55 for circulating water between said radiator and jacket, an air cooled radiator, and means for circulating water through said casing, in contact with said first named radiator, and through said air cooled radiator. 60

3. A cooling system for internal combustion motors, comprising an engine jacket, a radiator, an inclosing casing therefor, a condenser in communication with said radiator, an inclosing casing for said condenser, an air cooled radiator, means for circulating water between said inclosed radiator and jacket, means for circulating water between said radiator casing and air cooled radiator, and means for circulating water between 70 said condenser casing and air cooled radiator.

4. A cooling system for internal combustion motors, comprising an engine jacket, a radiator, an inclosing casing therefor, a condenser in communication with said radiator, an inclosing casing for said condenser, an air cooled radiator, means for circulating water between said inclosed radiator and jacket, means for circulating water between 75 said radiator casing and air cooled radiator, means for circulating water between said condenser casing and air cooled radiator, and thermostatic means, governed by the temperature of the water from the jacket, to 80 regulate the flow of cooling water to the radiator casing.

Signed at New York city, in the county of New York and State of New York this 28th day of June A. D. 1917.

LEON CAMMEN.
